ATTACHMENT FOR NEWSPAPER PRESS
INKING ROLLER SHAFTS

Arnold L. Imshaug, West Springfield, Mass., assignor to Alico, Inc., West Springfield, Mass., a corporation of Massachusetts

Application July 1, 1950, Serial No. 171,590

12 Claims. (Cl. 308—15)

1

This invention relates to an attachment for the shaft of an inking roller in a newspaper printing press.

The present application is a continuation in part of my pending application Serial No. 86,186, filed April 8, 1949, and now abandoned. Claims 1 to 5 of this application are the allowed claims of said former application. The reason for the present application is that I have devised certain novel structure which is not disclosed in the first application. The new structure is highly desirable from a commercial point of view and I wish to make a full disclosure of it. The structure in its broad aspects is the same in both applications.

Inking rollers on a newspaper printing press are heavy rubber covered cylinders weighing in the neighborhood of one hundred and fifty pounds. They are mounted as is well known in the art to distribute and spread the ink on an ink drum, to transfer the ink from the ink drum to intermediate distributor rolls, and finally to transfer an ink film from the latter to the press plate cylinders. There are several inking rollers in one press unit and all of them are more or less frequently removed from the machine for repair and replacement. The rubber facing may need to be re-surfaced; the roller may require truing or grinding; indentations may have injured the surface and require removal; a paper web may break and become wrapped around the rollers; the rollers may need re-setting for adjusting the contact pressure against a cylinder or drum. For any one or more of such reasons an inking roller is removed from time to time from its supporting brackets in the press.

The comparative frequency with which inking rollers are removed and installed have heretofore made the mounting of the same a particular problem with reference to the bearing supports for the roller shafts.

The usual support consists of a bracket having a socket with a split bushing therein to receive the end of a roller shaft. The upper half of the bushing is mounted in a cap member which is held clamped to a lower half of the bracket to hold the shaft for rotation in the bushing. Various arrangements for ball bearing support of the inking roller have been suggested without success in view of the necessity for frequent removal of the same. It is an object of my invention to provide an attachment permitting use of a ball bearing assembly.

A still further object is to provide an attachment which may be readily applied to inking

roller shafts already in use on existing newspaper press installations.

A further and specific object is to disclose an attachment construction in which the bearing assembly may be lubricated without removal of the inking roller from a press.

Other objects and advantages of the invention will be apparent from a consideration of the following specification in conjunction with the accompanying drawings, in which:

Fig. 1 is a sectional view of one form of attachment supported in a roller bracket with an inking roller shaft mounted therein;

Fig. 2 is an end view of the bracket holding the assembly;

Fig. 3 is a view similar to Fig. 1 showing a modified attachment structure;

Fig. 4 is a similar view of another modification of said structure; and

Fig. 5 is a similar view of still another form of attachment structure.

A usual mounting bracket 1 (Fig. 2) is attached to the frame of a newspaper press to support one end of an inking roller shaft, as will be readily understood by those skilled in the art. A similar bracket (not shown) supports the other end of the shaft. The holding means for the shaft comprises lower member 2 with a lower socket half 3 provided therein with a cap 5 pivotally joined as at 4 to member 2. Cap 5 is provided with an upper complementary socket half 6. The cap is held in clamped position by a wing nut and bolt assembly 7 pivoted as at 8 on member 2. A slot 9 is provided in the cap to receive the pivoted bolt in the clamping relation shown.

The clamping arrangement as thus far described is of the usual construction. For supporting the end of an inking roller shaft, however, in prior art construction, a split bushing is generally provided with each half thereof mounted in socket halves 3 and 6. The bushing supports a reduced end of the roller shaft for bearing support therein. The bushing as will be seen is not necessary to the combination of the present invention.

As shown by Fig. 1 a mounting stud 11 is held in clamped position within the socket of the bracket. Stud 11 comprises the mounting means for the new attachment. The other end of the attachment or coupling is in the form of an elongated sleeve portion 12 having a shouldered connection at 13 with the stud portion. At the inner end of the sleeve a reduced portion 14 is provided to receive a standard ball bearing as-

sembly 15. The bearing 15 is adapted for insertion as by a press fit and as shown carries the reduced stud end 16 of an inking roller shaft 17 for rotation therein. In this form of the device as in the other forms herein described the bearing as at 15 has an inner and outer race with antifriction rolling elements therebetween. The outer race supplies the stationary load support portion and the inner race supplies the load moving part of the bearing, the load moving part receiving the end of the roller shaft as at 16 to rotate the inking roller.

On shaft 17 and spaced from the inner end thereof is a cylindrical collar member 18. Collar 18 is fixed on the shaft as by a press fit and is located within the shaft encasing sleeve adjacent its opening. The collar extends radially of the shaft and is spaced slightly from the inner wall of the sleeve. Shaft 17 and collar 18 are thus freely rotatable within the sleeve with but a limited angular movement of the sleeve axis possible with respect to the axis of shaft 17. Longitudinal movement of shaft 17 outwardly of the sleeve is restricted by a stop pin 19 fixed in the wall of the sleeve adjacent its opening, the pin projecting inwardly to lie in the path of collar 18 between inking roller 20 and the collar. Pin 19 is threaded in the sleeve wall and is removable to permit withdrawal of the shaft for purposes of repair.

The provision for limited angular movement of the sleeve axis with respect to the axis of the roller shaft 17 permits removal of the inking roller from the press without buckling of the shaft support at the juncture of the bearing and roller shaft. In prior instances where ball and roller bearings have been installed as the journal connection for an inking roller shaft the removal of the clamping means has resulted in a buckling and twisting at the bearing socket connection thus causing displacement of the bearing races and dislodging of bearing balls. The weight of the inking roller and generally inaccessible position of the same on the press for manual support of the shaft immediately adjacent the roll cylinder portion causes a severe strain at the bearing connection whenever the axis of the bearing is not held in alignment with the roller shaft axis. Removal of a clamping member such as cap 5 of course releases its hold on a mounting stud when the pressmen are preparing to lift the roller from the press.

It will be appreciated that with the special structure herein described the mounting stud 11 will be maintained substantially in axial alignment with the roller shaft 17 whether clamped in the socket of the bracket or lying free of cap 5.

It will be further appreciated that the special structure as described may be readily adapted to inking rollers already in use on existing newspaper press installations. An ordinary roller shaft may be machined to provide a tip end as shown by Fig. 1 and the attachment assembly coupled on the end of the shaft.

A modification of the structure of Fig. 1 is shown by Fig. 3. It comprises several parts with a stud 21 for mounting in a bracket, a collar 22 fitted on the inner end of the stud and provided with exterior threading to receive the internal threading of an elongated sleeve 23 encasing the end portion of the shaft 24 of the inking roller 25. An inner shoulder 26 of the sleeve recess holds a bearing 27 between the shoulder and the collared end of stud 21. The end of shaft 24 is journaled in the bearing. Spaced from the end of the shaft and adjacent the opening of the

sleeve a radially extending pin 28 is fixed to the shaft. An inturned flanged portion 29 of the sleeve restricts withdrawal of the shaft outwardly of the sleeve, the shaft pin 28 acting as a stop. 5 The flange 29 being spaced slightly from the adjacent surface of shaft 24 acts to restrict angular movement of the sleeve axis and maintains the bearing alignment whether stud 21 is clamped in the socket or not. A slot 30 in the flange is provided for removal of the shaft 24 by permitting passage of pin 28 through the same.

Fig. 4 shows a further modification of the structure of Fig. 1. A mounting stud 31 for holding the attachment in the fixed support is provided with a circular cross-head or collar 32 at its inner end. The collar is threaded into an enlarged end opening of an elongated sleeve 34. The stud 31 is held securely in the opening by a lock nut 35. A shoulder 36 between the opening and the main portion of the sleeve 34 provides an abutment against which the outer race 36 of a ball bearing assembly is held by the face of cross-head 32. A reduced tip end 38 at the outer end of inking roller shaft 39 is encased by the inner race of the bearing.

A radially extending pin 40 is turned in the wall of sleeve 34 adjacent inking roller 41 and is positioned between the walls of an annular groove 42 in the shaft 39. A lubricating channel 43 in the stud 31 leads from a lubricant fitting 44 on the outer end of said stud to a recess 45 in the inner face thereof for convenient lubrication of the bearing assembly 37 without the necessity of removing the attachment from the stud 31.

35 The radial pin 40 with a reduced tip 46 permits free rotation of shaft 39 with the tip spaced from the walls and bottom of the groove 42. The pin will positively prevent relative longitudinal movement of the shaft and sleeve on removal of stud 31 from the clamping cap and socket of the bracket. The pin 40 may be removed if desirable and the frictional hold of the inner bearing race on the reduced end 38 may serve alone to maintain the shaft securely held by the bearing against relative longitudinal movement. The outer race or bearing support is held by a press fit within the cylindrical portion of sleeve 34 between the shoulder 36 and cross head 32. The end 38 is forcibly inserted in the inner race or load moving part with a tight frictional force fit and the bearing assembly itself is of sufficient strength to prevent ordinary longitudinal slipping of the sleeve with respect to the shaft.

Fig. 5 shows a form of attachment construction adapted for a press installation wherein limitations of spacing between the mounting bracket clamp and the end of the roller do not permit the use of a sleeve portion in the manner of Figs. 1, 3, and 4. The mounting bracket 1 is positioned in relatively closely spaced relation to the face end 47 of an inking roller. A stud 48 held in the bracket 1 has sleeve portion 49 carried integrally at its inner end.

60 A ball bearing assembly 51 is inserted as by a press fit in the inner end of sleeve 49 to surround a shortened end 52 of the inking roller shaft rotatably held in said bearing. A lubrication channel 54 and a fitting 55 at the outer end of the stud 48 is for lubricating the bearing.

65 In this form of attachment the outermost end of sleeve 49 is received in an annular recess 56 cut in the face end 47 of the roller. This construction of the attachment contemplates the modification of the roller end face so as to provide a shaft portion as at a shelf 57. The recess

56 may readily be tooled in a presently existing inking roller to accommodate the same to the attachment structure as shown. The interior cylindrical surface of sleeve 49 at the outer end thereof is closely spaced from the annular shelf 51 formed by the recess 56. The end 52 is inserted forcefully and tightly fitting the same in the bearing, as by driving the inner race over said end so as to resist any ordinary tendency to be shifted longitudinally. In lifting the roller by 10 the stud the outer ends of the sleeve portion 49 bear against the shelf 51 to prevent a sharp angular twisting of the bearing parts.

It will be seen that the various forms of attachment described may be used in converting existing roller shaft assemblies on various types of newspaper presses.

What is claimed is:

1. An attachment for a newspaper press inking roller shaft comprising, a mounting stud for holding the attachment in a fixed support, an elongated sleeve carried by the stud for encasing the end portion of the roller shaft, a bearing fixed in the inner end of said sleeve to receive the tip end of said shaft for rotation therein, a radially extending member fixed on the shaft adjacent the opening of said sleeve, said sleeve having retaining means at the opening thereof to prevent passage of said shaft member through the opening whereby said attachment is held against longitudinal movement with respect to said shaft and said shaft end is retained in said bearing.

2. An attachment for a newspaper press inking roller comprising, a shaft projecting from the end of said roller and rotatable therewith, a cylindrical collar fixed on the shaft and spaced from the end thereof, a shaft coupling having a recessed portion in the form of an elongated cylindrical sleeve receiving the end portion of said shaft with said collar projecting within the opening of said sleeve, a removable pin in the wall of the sleeve adjacent the opening and extending radially within the opening between the collar and roller to form a stop to limit longitudinal movement of said sleeve with respect to the shaft, and a ball bearing in the bottom of said recess receiving the tip end of the shaft, said coupling having means for mounting the same on a fixed support to hold said shaft end journaled in said bearing.

3. An attachment for a newspaper press inking roller comprising, a shaft projecting from the end of said roller and rotatable therewith, a cylindrical collar fixed on the shaft and spaced from the end thereof, a shaft coupling having a recessed portion in the form of an elongated cylindrical sleeve receiving the end portion of said shaft with said collar projecting within the opening of said sleeve, a removable pin in the wall of the sleeve adjacent the opening and extending radially within the opening between the collar and roller to form a stop to limit longitudinal movement of said sleeve with respect to the shaft, a shouldered inner narrowed portion in said recess having a ball bearing assembly mounted therein, the end of said roller shaft being journaled in the bearing, and said coupling having a cylindrical stud in axial alignment with said bearing and sleeve for mounting the coupling in a fixed support.

4. An attachment for a newspaper press inking roller shaft comprising, a mounting stud for holding the attachment in a fixed support, an elongated sleeve carried by the stud for encasing

the end portion of the roller shaft, a ball bearing fixed in the inner end of said sleeve to receive the tip end of said shaft for rotation in said bearing, said sleeve adjacent its opening having a flanged portion turned inwardly to restrict the mouth of said sleeve, and a radially extending pin on the shaft within the sleeve fixed adjacent the inner wall of said flanged portion of the sleeve.

5. An attachment for a newspaper press inking roller comprising, a shaft projecting from the end of said roller and rotatable therewith, a cylindrical stud shaft for mounting in a fixed support, a collar on one end of the stud having an externally threaded portion, a cylindrical sleeve threaded at one end thereof on said collar, said sleeve having a ball bearing adjacent said threaded end and receiving the end of said roller shaft in the bearing with the sleeve encasing the end portion of the roller shaft, a concentric flange at the open end of said sleeve in adjacent spaced relation to said roller shaft, and a projection on said roller shaft adjacent the flange to limit the longitudinal movement of said roller shaft within said sleeve.

6. An attachment for a newspaper press inking roller comprising a shaft projecting from the end of said roller and rotatable therewith, a stud shaft for mounting in a fixed support, a sleeve in axial alignment with and carried by the stud shaft and encasing the end of said roller shaft, said sleeve being in closely spaced and in immediately adjacent relation with a portion of said roller shaft, a bearing with rolling elements having a bearing support fixed in the inner end of said sleeve and a load moving part receiving the tip end of the roller shaft for rotation of said roller shaft within said sleeve, relative movement of the stud and sleeve from axial alignment with said roller shaft being limited by said closely spaced adjacent relationship in unsupported condition of said stud, whereby the stud shaft and roller shaft are maintained at all times substantially in axial alignment.

7. An attachment for a newspaper press inking roller comprising a shaft projecting from the end of said roller and rotatable therewith, a cylindrical stud shaft for mounting in a fixed support, a collar at one end of the stud having an external threaded portion, a cylindrical sleeve threaded at one end thereof on said collar, said sleeve having a bearing adjacent said threaded end with rolling elements and a load moving part receiving the tip end of said roller shaft with the sleeve encasing the end portion thereof in closely spaced immediately adjacent relation, and a lubricant passage in said stud shaft communicating with said bearing.

8. An attachment for a newspaper press inking roller shaft comprising, a mounting stud for holding the attachment in a fixed support, an elongated sleeve carried by the stud for encasing the end portion of the roller shaft, a bearing fixed in the inner end of said sleeve to receive the tip end of said shaft for rotation therein, said sleeve having a radially disposed member on said sleeve adjacent the opening thereof and an annular recess in said shaft for receiving the end of said member, whereby said attachment is held against longitudinal movement relative to said shaft and said shaft end is retained in said bearing.

9. An attachment for a newspaper press inking roller shaft comprising a mounting stud for holding the attachment in a fixed support, said stud having a hollow cylindrical portion slideable over the end of the roller shaft and permitting ro-

tation of said shaft within the hollow portion with said stud held fixed in axial alignment therewith, a bearing with rolling elements having a bearing support portion fixedly positioned in said hollow portion of the mounting stud and a load moving portion for receiving said roller shaft, the walls of the hollow portion of said stud remote from said bearing being closely spaced from the adjacent surface of said roller shaft to maintain said stud and roller shaft substantially in axial alignment.

10. An attachment for a newspaper press inking roller shaft comprising, a mounting stud shaft for holding the attachment in a fixed support, an elongated sleeve carried by the stud shaft for encasing the end portion of the roller shaft, a bearing fixed in the inner end of said sleeve to receive the tip end of said roller shaft for rotation therein and means to maintain axial alignment of said shafts.

11. An attachment for a newspaper press inking roller having a roller shaft projecting from the end of said roller and fixed for rotation therewith comprising, a stud shaft for mounting in a fixed support, a sleeve in axial alignment and fixed relation with said stud shaft, a bearing with a bearing support portion, a load moving part and rolling elements having said bearing support portion fixedly positioned in the inner end of said sleeve and the load moving part of said bearing for receiving the tip end of said roller shaft for rotation of the roller shaft within the sleeve, said sleeve adapted to be telescoped over

the roller shaft and to position the open end of the sleeve adjacent the end of said roller, with inner surface portions of the sleeve adjacent said open end in closely spaced relation to adjacent surface portions of the roller shaft to maintain the roller and stud shafts substantially in axial alignment in supported and unsupported condition of the stud shaft.

12. An attachment for a newspaper press inking roller shaft comprising, a mounting stud shaft for holding the attachment in a fixed support, an elongated sleeve carried by the stud shaft for encasing the end portion of the roller shaft, a bearing fixed in the inner end of said sleeve to receive the tip end of said roller shaft for rotation therein means to maintain axial alignment of said shafts, and releasable means to prevent longitudinal separation of said shafts.
